UNITED STATES PATENT OFFICE.

DANIEL COLLINS, OF BAKER, OREGON.

PAPER-PASTING MACHINE.

Application filed October 30, 1922. Serial No. 597,881.

To all whom it may concern:

Be it known that I, DANIEL COLLINS, a citizen of the United States, residing at Baker, in the county of Baker and State of Oregon, have invented certain new and useful Improvements in Paper-Pasting Machines; and I do hereby declare the following to be a full, clear, and exact description of the invention, such as will enable others skilled in the art to which it appertains to make and use the same.

This invention relates to a paste-applying machine.

It is particularly aimed to provide a novel machine whereby wall paper as it is unrolled for use or to be cut into lengths will automatically receive an application of paste or adhesive so as to overcome the present manual method in view of the time lost and expense incurred incidental thereto.

It is further aimed to provide a reservoir to contain the paste or adhesive and in which an applicator roller is disposed, together with means on the reservoir to mount a roll of paper in constant yieldable contact with the applicator roller, an idler on the reservoir over which the paper passes and a scraper means for excess adhesive on the paper located adjacent the idler roll.

With the above and additional objects and advantages such as will be pointed out or be apparent from a consideration of the following description, in view, the invention has been embodied in one preferred form as illustrated in the accompanying drawings.

In said drawings:—

Figure 1 is a view in side elevation illustrating the invention in connection with a paper hanger's table;

Figure 2 is a plan view of the paste-applying mechanism;

Figure 3 is a central longitudinal sectional view on line 3—3 of Figure 2, and

Figure 4 is a detail perspective view showing the separable connection between the paper roll and supporting arms therefor.

Like reference characters designate like or similar parts in the different views.

In reducing the invention to practice, a tank or reservoir of suitable shape and size is provided as at 10 and being open at its top as shown. A roll about which wall paper or the equivalent 11 is wrapped is shown at 12 and adapted for detachable mounting in supporting arms 13 pivoted as

at 14 to and within the reservoir 10. Such detachable mounting may be accomplished in many ways and for example one arm 13 may have a socket 15 to receive one end of roller 12 while the other arm may have an open end socket or slot 16 to receive the other end of said roller.

A paste or adhesive applicator is shown within the reservoir 10 as being a roller 17 having a shaft or trunnions 18 journaled in the side walls of the reservoir. The paper 11 as it is unwrapped from roller 12 passes at its pasting side or surface over and in direct contact with roll 17 as shown, and as said roll travels in the paste or adhesive contained in said reservoir as shown, the periphery of the roll 17 transfers the paste or adhesive automatically and evenly to said pasting surface of the paper.

An idler roll 19 by means of a shaft or trunnions 20 is rotatably journaled in bearing plates 21 secured to the side walls of reservoir 10 and extending above the same. These bearing plates 21 have inclined upper surfaces along which a plurality of notches 22 are provided and in which the trunnions 20 may be disposed selectively and at different heights. Paper 11 is adapted to travel beneath and around idler 19 as shown.

Intermediate the roll 17 and idler 19 a scraper blade 23 is disposed so that the pasted surface of the paper will contact therewith as it passes through the machine in order to scrape or remove surplus adhesive therefrom, causing it to fall back into the supply with the reservoir. Blade 23 is preferably of metal and it may have arms 24 integral therewith screwed or otherwise fastened to the walls of the reservoir as at 25.

Disposed between the idler 19 and scraper 23 is a spreader and smoother that comprises a bar 26 of any suitable material, preferably wood, supported on the side walls of reservoir 10 and covered with one or more layers of cloth, felt, or other suitable material 27. The purpose of the spreader or smoother is to evenly distribute the paste on the paper and to smooth its surface, as well as to remove any surplusage of paste that may remain on the paper that might be left by the scraper 23.

Paste or adhesive may be poured into the reservoir 10 through its open top or prepared and mixed within said reservoir as preferred. Prior to inserting a roll of

2
paper, idler 19 is removed and after the paper roll is mounted in the arms 13, it is partially unwrapped, passing over the applicator 17 and the idler is then restored to the operative position as shown in the drawings. The paper may then be freely unwrapped and cut into lengths or otherwise for use or application to a wall. As arms 13 are pivoted as shown, the roll 11 tends to move toward applicator 17 automatically to insure effective engagement of the paper with the applicator as the diameter of said roll decreases. While not necessary, yet it is preferable to use a table A in connection with the machine so as to hold the free end of the paper for measuring, cutting or the like. The top of the table shown may consist of an endless web B of canvas or other flexible material mounted by rotatable rolls 20 C thereon which enables the web to travel as the paper is pulled over the web in order to reduce friction to the minimum.

As merely one operative embodiment has been illustrated and described, it is to be understood that changes in the details may be resorted to provided they fall within the spirit and scope of the invention.

What is claimed is:—

1. An adhesive-applying machine having a reservoir to contain adhesive, an applicator to travel in the adhesive and transfer the same to material passed thereover, an idler under which the material passes, and bearing means for the idler having a plurality of bearing notches at different elevations for mounting the idler.

2. An adhesive-applying machine having a reservoir, an applicator roll rotatably mounted in the reservoir, arms pivoted to the reservoir at one side of the applicator, a roll about which material is adapted to be wrapped detachably mounted by said arms, the weight of the roll and material maintaining said arms out of the vertical and urging them at their free ends toward the applicator, the material adapted to pass over the applicator, an idler under which the material passes, a bearing having a plurality of notches at different elevations to selectively mount the idler, and a blade to scrape surplus adhesive from the material disposed in the reservoir intermediate the applicator and idler.

In testimony whereof I affix my signature.

DANIEL COLLINS.
